Inc., Los Angeles, Calif., a corporation of California

Filed Nov. 20, 1961, Ser. No. 67,591

Term of patent 14 years

(Cl. D30—1)

FIG. 1 is an elevational view of one side of a gun recoil cushion embodying our new design, the opposite side of the cushion being the mirror image of that illustrated;

FIG. 2 is a front elevation of the cushion;

FIG. 3 is a rear elevation of the cushion;

FIG. 4 is a top plan view of the cushion;

FIG. 5 is a bottom plan view of the cushion; and

FIG. 6 is a fragmentary perspective view illustrating the depth of the recesses in the sides of the cushion.

We claim:

The ornamental design for a gun recoil cushion, as shown and described.
